UNITED STATES GYPSUM COMPANY, OF CHICAGO, ILLINOIS, A CORPORATION OF
ILLINOIS

WALL BOARD

Application filed March 15, 1926. Serial No. 94,796.

This invention relates to wall boards and more particularly plaster or composition boards, although it is equally applicable to different kinds of building boards such as 5 those made of paper or pulp, and is even applicable to wood boards, particularly if they be used in the manner commonly employed in connection with wall board construction of partitions, etc. In such construction boards 10 of suitable widths are usually secured to or mounted in walls, frame work, or studdings, in edge to edge relation and often form the foundations for plaster work.

In such constructions, damage to the plaster or wall boards, due to nailing, shrinking of the boards, stuffings, or for other reasons, often results in the regions of the joints of such boards, or, due to the usage which the boards receive prior to and during installation; and also, often due to the moisture contained in the plaster coat when applied thereto, the edges of the boards are damaged.

It is, therefore, evident that protection of the edges of the wall boards against damage 25 by nailing contact or by moisture is desirable, and furthermore, the reinforcing of such edges is also desirable especially in cases where a number of boards are arranged edge to edge, one above the other, and are required to support weight upon their lower edges.

This invention therefore has for its object to provide simple and effective means incorporated in wall boards to meet the different 35 conditions hereinbefore referred to and to provide a wall board wherein adequate reinforcement and protection of the longitudinal edges is assured.

In carrying this invention into effect, I may 40 adopt any of the novel constructions and arrangements of parts hereinafter described by way of example, having reference to the accompanying drawing, wherein

Figure 1 is a perspective view of a wall board embodying the said invention;

Figure 2 is a transverse section of the same;

Figure 3 is a fragmentary detail sectional view of the same illustrating the method of securing the reinforcing channel to the edges 50 and providing nailing facilities;

Figure 4 is a fragmentary perspective view with part of the reinforcing channel removed;

Figure 5 is a fragmentary perspective view of a wall board showing a modified form of channel;

Figure 6 is a perspective view illustrating a still further modified form of the same;

Figure 7 is a perspective view showing another modification; and

Figure 8 is a fragmentary transverse section of the form shown in Figure 7.

Similar characters of reference indicate similar characters in the several figures of the drawing.

1 is a wall board which in this case is indicated as being of the type having a plaster or composition core 2 and paper faces 3 and 4, and the opposite longitudinal edges of this board are provided with reinforced means shown in Figures 1, 2, 3 and 4, as comprising 65 channel strips 5, the edges of which overlap the edges of the wall boards, it being intended that these strips be applied to the board when it is manufactured and the board sold as a new article of manufacture comprising a wall 70 board having specially reinforced edges.

The channel strips may be of the form shown in Figure 4 and the same length as the board, the edges of the strip being passed over the margins of the board in its application thereto; or it may be formed from a flat strip directly on to the marginal edge of the board by bending or rolling operations commonly known to sheet metal workers, and suitably secured against accidental removal 75 from the board. For example, as shown in Figures 1 and 3, the marginal portions of the reinforcing strips 5 may be provided with a series of depressions 6 whereby the material

from which the reinforcing strips are formed is firmly engaged with the marginal parts of the board and also whereby nailing facilities are provided, such depressions forming nail 80 ing guides and also providing for the weakening of the reinforcing material at such points so that nails may be readily driven therethrough when the boards are being applied to a building or otherwise put into use.

These reinforcing strips may be continuous 100 throughout the length of the board as shown

in Figure 1, or may be cut or weakened as at 7 in Figure 5, to facilitate the separation or the severing of the strip intermediate of its length if it be desired to cut the board to shorter lengths, as will be readily understood, this form of strip being indicated in Figure 5 by the reference numeral 5^a.

Also different methods may be adapted of securing the strip to the board, such as in Figure 6, where a reinforcing strip 8 is shown as having its edges 9 bent inwardly of the board so that they are pressed into the face thereof, as shown.

Figures 7 and 8 indicate a fabric reinforcement 10 which may be secured in position by means of an adhesive or such similar means and may be coated or filled with water-proof or moisture resisting material to protect the edge of the board against the access of moisture thereto. This reinforcement 10 may be of wire fabric and be secured in position by pressing into the surface of the board or otherwise, and in such case may assist in the bonding together of the adjacent edges of boards when they are plastered as in building construction.

Many different materials may be employed in the reinforcement of the longitudinal edges of the board as suggested and various means adapted for the securing of such reinforcement in position according to convenience or requirements, and this invention may be developed within the scope of the following claims without departing from the essential features of said invention, for which reason it is desired that the specification and drawings be read as being merely illustrative and not in a limited sense except as necessitated by the prior art.

What I claim is:—

1. As a new article of manufacture, a wall board for building construction, said wall board having a rigid channel shaped transversely divisible reinforcing strip overlapping opposite edges thereof.
2. In an article of manufacture, a wall board for building construction, said wall board having a channel shaped reinforcing strip overlapping opposite edges thereof, portions of said strip being depressed into the surface of the wallboard to secure said strip against detachment therefrom.

In testimony whereof I affix my signature.
CURRY O. WALPER.
